CLAIM

The ornamental design for a docking system and mixer for portable media devices, as shown and described.

DESCRIPTION

FIG. 1 is a perspective view of a docking system and mixer for portable media devices showing our new design;

FIG. 2 is a front elevational view thereof;

FIG. 3 is a rear elevational view thereof;

FIG. 4 is a top view thereof;

FIG. 5 is a bottom view thereof;

FIG. 6 is a left side elevational view thereof;

FIG. 7 is a right side elevational view thereof; and,

FIG. 8 is a perspective view thereof with a portable media device installed therein. The broken line showing of the portable media device is for illustrative purposes only and forms no part of the claimed design.
